SCREEN FOR BALL MILLS

Application filed January 11, 1928. Serial No. 245,836.

This invention relates to screens for ball mills, cement pulverizing drums or any other form of rotating drums which employs crushing media or tumbling work. However, it is particularly directed to the ball tube mills used in preparing the raw material and finishing cement in a cement mill.

In the drawings:

Fig. 1 is a fragmentary perspective view partly in section of a ball tube mill.

Fig. 2 is an elevational view of one of the segments of the screen.

Fig. 3 is a section on the line 3—3 of Fig. 2.

In cement mills it is customary to crush or grind the marble or limestone and clay and grind the cement clinker by means of what is called a ball tube mill. This is a long drum or tube which is divided into one or more compartments by means of screens or diaphragms. Within these compartments are a load of balls, slugs, or other crushing media. They are raised by the rotating drum and dropped on the material being worked upon. They are consequently deforming and abrading the screens or perforating diaphragms that guard the outlet end of the compartment or divide one compartment from another. These screens soon wear and have to be replaced due to the constant abrading action of the balls and the work. The openings through the screens become choked and clogged due to the peening of the metal at the edges of the openings by the action of the balls.

It is the object of the present invention to so form the openings of the screens that they are not subject to a peening action which will clog the openings. This is accomplished in two ways, namely, by the arrangement and disposition of the openings, and secondly, by the shaping or flaring of the openings so that the peening action, if any, is away from the opening.

a designates the revolving drum or tube of a conventional mill. However, the character of the drum may be varied within wide limits as there are numerous different kinds of mills now on the market; it simply illustrates one form. *b* is a screen or perforated diaphragm which is somewhat concave in

the usual fashion. *c* designates a segment or one of the plates that form into the diaphragm. This is provided with a plurality of openings *d* which are truly concentric to the center of the diaphragm. This makes the long way of the hole directly parallel to any point of the rotating mass, and consequently, cuts the abrading action down to a minimum.

These screens or plates are relatively heavy to withstand the heavy shocks incident to the falling of the work and the balls upon the plates, being approximately two inches thick and often still thicker. Referring to Fig. 3, the character of the cross section of our improved segment will be seen. The openings on the side through which the work is fed are flared as at *e* at about a 45° angle, and the plate surface between adjacent openings is rounded over as at *f* to form a convex crown. At *g* the opening is "metered" that is, at this point the opening or perforations through the plate are of the size desired in establishing the capacity or what might be said to be the mesh of the screen. From this point the back of the opening flares out gradually as at *h* to enlarge the capacity of the hole to prevent clogging after the material has passed through the "metered" zone.

We construct the screens of a tough material preferably a high manganese steel, but so far as the broader features of the invention are concerned we do not care to be limited to a particular kind of steel. The plate is preferably a casting. We find the openings constructed as above described resist successfully the tendency to choke or cut down the cross section of the opening due to the peening action of the work and the balls. Any peening that does take place is on the crowns that intervene between the openings. The "metered" zone of the openings is removed about a half an inch from the surface and is therefore located in the solidest mass of the plate. On the other hand by flaring the openings on practically a 45° angle and locating them fairly close together narrow crowns are provided on the plate. These by reason of their dimensions are much easier to distort than

that portion of the metal adjacent the "metered" zone of the openings. The result is that such peening action as does occur is naturally in the direction of the crowns and hence any distortion of material works towards the crown rather than down into the metered openings. On the crowns it is worn off gradually by the abrasion of the work and the material, and consequently in no way tends to clog the openings.

10 We find it desirable to stagger the opening as clearly shown in Fig. 2. This adds to the strength of the plate and also we find it desirable in carrying out our plan to confine the peening entirely to the surface of the plate and keep it out of the "metered" portions of the openings.

15 We find that the flaring serves three functions in resisting the clogging of the "metered" portion of the openings: first, it avoids all sharp or weak corners which may be easily peened over; secondly, it removes the "metered" portion of the opening far into the interior away from the peening action; and 20 third, it forms weakened crowns between the flared openings which are arranged first to give way in response to any peening action and therefore save the distortion of the metal into the "metered" openings.

25 30 We have found that plates constructed in accordance with our invention are capable of withstanding service for upwards of a year, whereas plates built according to the common custom of the trade will last only a few weeks 35 when these will have to be repaired or replaced due to the choking of the openings by the peening action.

30 By the word "metered" we do not wish to 40 convey the impression of technical accuracy of these metered zones but simply that this is a zone which has a predetermined cross section for the purpose of screening the material.

45 What we claim is:

1. In rotating ball mills or the like, a screen 50 comprising a plate having a plurality of openings therethrough which are relatively long and narrow, each of said openings being bounded by oppositely converging walls which converge inwardly from the ends of 55 opening, said opening having a metered portion connecting the oppositely converging walls, said plurality of openings being disposed so that the lengthwise dimensions substantially parallel an arc having the axis of the mill as a center, whereby the balls in the 60 mill move across the openings in a direction substantially paralleling the length of the openings to minimize the peening action on the edges of the opening.

60 2. In rotating ball mills or the like, a screen 65 comprising a plate having a plurality of openings therethrough which are relatively long and narrow, each of said openings being bounded by oppositely converging walls which converge inwardly from the ends of

the opening, said opening having a metered portion connecting the oppositely converging walls, said plurality of openings being disposed so that the lengthwise dimensions substantially parallel an arc having the axis of 70 the mill as a center, whereby the balls in the mill move across the openings in a direction substantially paralleling the length of the openings to minimize the peening action on the edges of the opening, said openings being 75 uniformly arranged, and relatively close to each other, to provide relatively narrow, weakened, and uniform crowns between them, which extend substantially parallel to an arc having the axis of the mill as its center, for 80 receiving the peening action.

3. In rotating ball mills or the like, a screen comprising a plate having a plurality of openings therethrough, which are relatively long and narrow, each of said openings having an inlet end which is bounded by inwardly converging walls, each opening having a metered portion inwardly of the said converging walls, said openings being disposed so that their lengthwise dimension substantially parallels an arc having the axis of 85 the mill as a center, whereby the balls in the mill move across the openings in a direction substantially parallel with the length of the openings and contact with the said converging walls to minimize the peening action.

35 In testimony whereof we affix our signatures.
